LIGHTING FIXTURE

Hugh J. Claspy, Monaca, Pa., assignor to Phoenix Glass Company, Monaca, Pa., a corporation of West Virginia

Application August 28, 1940, Serial No. 354,525

3 Claims. (Cl. 240—128)

My invention relates to lighting fixtures and more particularly to light transmission shields of glass or other transparent or semi-transparent material for enclosing or shielding fluorescent lamp tubes or other types of lamp tubes.

Briefly stated, my invention comprises a shield or trough of glass or the like, together with means for supporting it in position beneath a lamp tube or tubes, in an improved manner, and constitutes a modification of the invention disclosed in my application Serial No. 354,526, filed August 28, 1940.

One object of my invention is to provide a shield and a holder of such form that they can readily be applied to various standard forms of lamp structures, and whereby the shield can easily be applied and removed, without the necessity of operating holding screws or metal clips, or similar devices.

Another object of my invention is to provide an arrangement whereby stock lengths of shield elements can be employed in connection with lamp tubes of various lengths, rendering unnecessary the forming of shield elements of certain particular lengths to fit over each of various lengths of lamp tubes.

As shown in the accompanying drawing, Figure 1 is a cross-sectional view through an illuminating unit embodying my invention; Fig. 2 is a face view of a portion of a trough or shield element; Fig. 3 is a face view of a joining ring or yoke, for the shield elements; Fig. 4 is a sectional view on the line IV—IV of Fig. 1; and Fig. 5 is a side view of a unit, on a reduced scale.

The shield is shown as mounted beneath a fluorescent tube 5, that is supported by suitable sockets and bracket elements 7 and 8 that are in turn supported from a ceiling by hanger rods 6 that may serve as wiring conduits, in any of well known conventional ways, the wiring and other detail parts being omitted herefrom, since they form no part of my invention.

A holder 9 which also serves as a cover plate, is supported by the bracket element 8 and extending throughout the length of the tube 5, it being understood that it is common practice to employ a plurality of lamp tubes 5 in a single unit. The member 9 is of generally channel form and has flanges 10 and 11 for supporting the shield.

The shield is shown as composed of a plurality of elements 12, formed of glass or other transparent or translucent material, such as various of the molded plastics. The elements 12 are shown as provided with ribs, flutes or the

like, as indicated at 13, that serve to refract the light and also as ornamentations. The elements 12 are made of suitable length, so that two or more of them can be assembled endwise with respect to one another, in order to provide a shield of length sufficient to cover the lamp tubes, which tubes are made in various lengths.

Each unit 12 has flanges 14 formed on its longitudinal edges, for engagement with the flanges or ledges 10 and 11, so that vertical support is thereby provided for the elements. The flanges 14 are of such width that they will not become dislodged from the flanges 10 and 11 through sidewise sliding or shifting of the elements. When it is desired to remove an element 12 from the holder 9, one side thereof is raised a slight distance, as indicated by the arrow 15, whereupon the element can be slid slightly in the direction indicated by the arrow 16, because of the clearance provided at 17 beneath the flange 14. By this combined lifting and lateral sliding movement at one edge of the unit 12, the flange 14 at the opposite edge will be shifted clear of the ledge 11, whereupon that side of the element 12 can be lowered out of the holder 9 and the element thus removed from the holder.

Adjacent ends of the elements 12 are recessed or flanged as shown at 18, to receive the flanges of a joining ring or yoke 19, that is of T-shape in cross section, the leg or stem 20 of the member 19 extending between the extremities of adjacent elements 12. The member 19 has a flange 21 formed on each of its ends, corresponding to the flanges 14 at the front and rear edges of the elements 12. These yokes 19 are inserted and removed from the holders by a combined raising, lateral shifting and tilting movement, as are the elements 12. Ordinarily they will be placed in position after the elements 12 are inserted in the holder. Also, after removal of one element the yokes can be slid longitudinally of the ledges, to free an adjacent element for removal. Also, the shield elements can be slid longitudinally relative to the yokes. To provide continuity of pattern or appearance when desired, the yokes 19 have ribs or flutes 22 formed thereon in longitudinal alignment with the flutes and ribs 13.

The yokes or joining elements 19 conceal the space which would otherwise be present between adjacent ends of the elements 12 and also obstructs the light rays which would otherwise pass between such ends, as well as assisting in keeping out dust. The endmost shield elements 12 have end walls 23 formed thereon, but end walls of

metal plates or the like can be employed for closing the extremities of the shield.

I claim as my invention:

1. A lamp shielding device comprising horizontally-disposed shield-holding flanges and means for supporting them at opposite sides of a lamp, outwardly-bowed shield elements of trough-like form having their longitudinal edges disposed behind the said flanges and outwardly-bowed joining elements having their extremities disposed behind said flanges, the adjacent ends of the shield elements extending behind the joining elements, and clearance being provided between the innermost edges of said flanges and the adjacent sides of the shield elements and joining elements, along lines spaced downwardly from their said edges and extremities, whereby when one edge of each element is lifted a slight distance, said element can be slid laterally to move the opposite edge thereof from behind its associated shield-holding flange, to permit removal of the said elements from the shield-holding flanges.

2. A lamp shielding device comprising horizontally-disposed shield-holding flanges and means for supporting them at opposite sides of a lamp, outwardly-bowed shield elements of trough-like form having their longitudinal edges disposed behind the said flanges, and outwardly-bowed joining elements having their extremities disposed behind said flanges, the adjacent ends of the shield elements extending behind the joining elements, and clearance being provided between

the innermost edges of said flanges and the adjacent sides of the shield elements and joining elements, along lines spaced downwardly from their said edges and extremities, whereby when one edge of each element is lifted a slight distance, said element can be slid laterally to move the opposite edge thereof from behind its associated shield-holding flange, to permit removal of the said elements from the shield-holding flanges, the said elements being slidable longitudinally on said flanges.

3. A lamp shielding device comprising horizontally-disposed shield-holding flanges and means for supporting them at opposite sides of a lamp, outwardly-bowed shield elements of trough-like form having their longitudinal edges disposed behind the said flanges, and outwardly-bowed joining elements having their extremities disposed behind said flanges, the adjacent ends of the shield elements extending behind the joining elements, and longitudinal depressions being provided in the sides of said elements, along lines spaced below their said edges and extremities, whereby when one edge of each element is lifted a slight distance, said element can be slid laterally to move the opposite edge thereof from behind its associated shield-holding flange, to permit removal of the said elements from the shield-holding flanges, the said elements being slidable longitudinally on said flanges.

HUGH J. CLASPY.
